Harlow M. Davis

UNITED STATES PATENT OFFICE

2,040,829

MACHINE FOR ROUGHING SHOE PARTS

Charles G. Brostrom, Lynn, Mass., assignor to
 United Shoe Machinery Corporation, Paterson,
 N. J., a corporation of New Jersey

Application October 30, 1933, Serial No. 695,796

9 Claims. (Cl. 69—1)

This invention relates to roughing machines and particularly to machines for roughing shoe parts such, for example, as the overlasted margin of the upper of a lasted shoe, to prepare the surfaces of such parts for the reception of the cement which, in certain methods of shoemaking, is employed for attaching other shoe parts, as outsoles, thereto.

In roughing the overlasted portion of the upper of a lasted shoe difficulty is sometimes encountered in operating uniformly and to just the right degree upon the delicate upper leather, by reason of the irregular shape of the surface to be operated upon and the fact that, particularly in the shank portion of the shoe, a concavely curved surface is presented which requires the exercise of considerable skill by the operator who attempts to perform the roughing operation with the commonly used rotating wire brush.

It is an object of the present invention to provide an improved roughing machine which will so facilitate the roughing operation that the average operator will be easily able to produce uniformly good work with less necessity for the exercise of skill than has heretofore existed when using the machines which have been available.

This object is accomplished by the provision of a novel roughing tool which, in the illustrated embodiment of the invention, comprises a large number of wire bristles arranged in diagonally flaring relation to the axis of rotation of the tool and supported in a tool head of such configuration that a shoe of any size or shape may be easily and accurately presented to and moved past the tool. The organization and disposition of the tool are also such that the visibility of the portion of the work which is being operated upon is enhanced, making it easy for the operator to observe closely how the operation is proceeding, and consequently facilitating the production of an accurately outlined uniformly roughed area upon the surface of the work.

Another important improvement effected by the present invention consists in tremendously increasing the life of the roughing tool. The wire brushes heretofore used have had a comparatively short life, it having been found necessary to discard them when only a small proportion of the length of the bristles had been worn away, because by that time many of the bristles had become bent and the degree of resiliency of those remaining had become so altered by the reduction in their length as seriously to affect the manner in which they operated upon the leather. A tool constructed in accordance with the present in-

vention will actually outlast a large number of the wire brushes of the older type and will have substantially uniform operating characteristics throughout its entire life. This very desirable improvement is secured in the illustrated roughing tool by the use, as bristles, of very long crimped wires arranged in a plurality of bundles mainly disposed parallel to the axis of rotation of the tool but having their outer ends deflected and held outwardly at a considerable angle thereto.

The rear ends of the bundles of wires are preferably secured in an axially movable ring which may be readily adjusted longitudinally of the tool-carrying shaft so that as the working ends of the wires gradually wear away they may be fed forward with the result that any desired amount of projection of the wires from the surface of the tool head may be maintained until the wires are practically used up. By grouping the wire bristles in bundles into which the wires may be tied in separate collections or groups, insurance is provided against the wires becoming entangled with each other and the surface of the work being operated upon can be easily seen while the tool is rotating rapidly, which would not be the case if a solid mass of wires were employed.

By employing crimped wires the springiness of the bristles is materially improved and this, together with the provision for easily and quickly adjusting the amount by which the bristles project from the tool head makes it possible to adjust the "feel" and effective stiffness of the tool to secure the best results with the many different kinds of leathers which are used in making the uppers of shoes.

These and other objects and features of the invention will be better understood and appreciated from reading the following detailed description of one embodiment thereof in connection with the accompanying drawings, in which—

Fig. 1 is a view in front elevation, partly in section, of a shoe upper roughing machine embodying the invention;

Fig. 2 is a view illustrating the relation of the roughing tool to the work as seen by the operator;

Fig. 3 is a view in elevation, partly in section, of the roughing tool head with the parts thereof somewhat separated;

Fig. 4 is a perspective view of the principal parts of the roughing tool head; and

Fig. 5 is a view showing a detail of one of the bundles of wire bristles.

In the drawings, 10 indicates a supporting column upon which is bolted a base 12 provided with bearings 14, 16 for a rotating shaft 18 which may be driven by a belt 20 passing around a pulley 5 22 secured by a key 24 and a set screw 26 to the shaft.

As illustrated, the shaft 18 is hollow throughout most of its length, consisting practically of a tube having one solid end, as shown at 28 in 10 Fig. 1. A long screw 30 is arranged to turn freely in an axial hole which passes through the solid end 28 of the shaft 18, and secured to the left-hand end of said screw, as seen in Fig. 1, is a knurled head 32 by means of which the screw 15 may be easily turned relatively to the shaft 18.

Threaded upon the screw 30 is an adjusting ring 34 which is longitudinally slidable in the hollow bore of the shaft 18 and is prevented from turning relatively thereto by a spline 36. This adjusting ring 34 is provided with eyes through which are passed the groups of wires constituting the bristles of the roughing tool. Fig. 5 shows one of these groups of wires as it appears after it has been passed through one of the eyes in the ring 34 and bent back upon itself to form a compact bundle 37 of wire bristles. Each such bundle is tied at intervals as indicated at 38 in Fig. 1 in order to keep it separate from the other bundles of bristles and thus to prevent the large 30 number of wires in the hollow shaft 18 from interfering or becoming entangled with each other.

Initially the bundles of wires 36 are long enough to reach from the adjusting ring 34 when the latter is at the left-hand end of its travel upon 35 the screw 30, as seen in Fig. 1, to and substantially beyond the open right-hand end of the shaft. The right-hand end of the shaft 18 carries the roughing tool head which will now be described in detail.

40 Referring particularly to Figs. 1, 3 and 4, 40 indicates a cylindrical peripheral surface at the right-hand end of the shaft 18 into which is set a key 42. A bristle-guiding member 44 has an internal cylindrical surface which is a sliding fit 45 upon the surface 40 of the shaft and a key-way 48 arranged to engage the key 42 so that the guide member 44 can be pushed upon the end of the shaft 18 but cannot turn relatively thereto. An internal shoulder 50 engages the end 52 50 of the shaft and limits the extent to which the member 34 can be pushed thereon.

A sleeve 54, which surrounds the shaft and has an internal shoulder 56 engaging a shoulder 58 upon the shaft, may be screwed upon the externally threaded portion 60 of the member 44 to draw the latter accurately and firmly against the end of the shaft. The guide member 44 is provided with a plurality of outwardly directed openings 62, 64 designed to receive the respective 60 bundles of wire bristles 37. These openings flare outwardly from the axis of the shaft, the alternate openings 62 making a greater angle with the said axis than the intermediate openings 64 so that the openings are staggered relatively to each other, considered circumferentially of the bristle-guiding member 44.

Cylindrical surfaces 66 and 68 are formed upon the guide member 44 which also has a screw threaded extension 70 pierced with an axial hole 72 which receives the reduced pilot 74 upon the end of the screw 30 for the purpose of supporting the screw in the axis of the shaft 18.

A bristle-clamping ring 76 is arranged to fit upon the cylindrical surfaces 66, 68 of the member 44 and is secured to said member by screws 75

78 passing through holes 80 in the ring and screwed into threaded openings 82 in the member 44. The ring 76 has bristle-receiving openings 84, 86 in register, respectively, with the openings 62, 64 in the member 60, the openings in the ring being formed as slots or channels which receive corresponding clamping blocks 88, 90 formed upon a bristle-clamping plate 92 provided with a central opening 94 large enough to slide over the extension 70 of the member 44. A nut 96 is adapted to be screwed upon the end of the threaded extension 70 to bear against the clamping plate 92 and cause the blocks 88, 90 to be pressed tightly against the bundles of wire bristles 36. The above-described bristle-guiding member 44, clamping ring 76 and clamping plate 92, may be said to constitute a frusto-conical bristle-holding tool head and are clearly shown in their assembled relation in Fig. 1.

The bundles of wire bristles 37 may be properly assembled with the adjusting ring 34, the said ring started upon the screw 32 and, by turning the screw, drawn into the hollow shaft 18. The bristle-guiding member 44 with the clamping ring 76 secured to it is then mounted upon the end 20 of the shaft, the individual bundles of wire bristles being directed outwardly through the respective openings in the member 44 and the clamping ring and the clamping plate 92 placed in position. The nut 96 is not drawn up tightly until the bristles have been adjusted to project the desired amount from the periphery of the roughing tool head, which adjustment may easily be accomplished by turning the screw 30. The nut 96 is then tightened and the bristles are securely held in adjusted position by the blocks 88, 90 upon the clamping plate 92. Whenever it is desired to change the adjustment of the bristles, it is only necessary to loosen the nut 96, adjust the bristles by means of the screw 30 and adjusting ring 34 and again tighten the nut 96.

Secured in brackets 98, 100 rising from the bearings 14, 16 is a rigid bar 102 which supports a tubular shield 104 for protecting the knurled head 32 of the screw 30 when the shaft is running.

The shield 104 is at the outer end of an arm 106 carried by a hub 108 which is slidably mounted upon the bar 102, a spring 110 being interposed between the bracket 98 and the hub 108 and tending to move the hub 108 toward the left, as viewed in Fig. 1, to a position in which the shield 104 covers a screw head 32 and the end of the rotating shaft 18, as shown. A set screw 112 is provided to secure the hub 108 to the bar 102 when 55 desired. When access to the head 32 of the screw 30 is required for the purpose of making adjustments the shield 104 is moved toward the right and when released it automatically returns to the position shown.

A dust-removing hood 114 and a bristle-sharpening apparatus 116 are provided, but these are fully described in United States Letters Patent No. 1,989,078 granted upon my copending application Serial No. 594,529, filed February 23, 1932, 65 and need not be described in detail here.

Having described my invention, what I claim as new and desire to secure by Letters Patent of the United States is:

1. A rotary roughing brush having long bristles 70 mainly disposed parallel to the rotational axis of the brush and having their work engaging end portions turned outward from said axis, and means for adjusting said bristles lengthwise of the brush.

2. A rotary roughing tool having a tool head, bristles of crimped, resilient wire adjustably clamped in said head, and means for moving the bristles through the head, to vary the effective stiffness of the bristles to adapt them to work of different kinds.
3. A rotary roughing brush having a brush head, bristles arranged in a plurality of separate bundles with the ends of said bundles projecting 10 in staggered relation around the brush head, and means for simultaneously varying the amount of projection of all of said bundles of bristles from the brush head.
4. A rotary roughing brush having long bristles 15 mainly disposed parallel to the rotational axis of the brush, a brush head in which the work engaging end portions of the bristles are held turned outward from said axis, and an axially adjustable ring in which the inner ends of the bristles are 20 secured.
5. A rotary roughing tool for shoe parts comprising a tool head having guide openings therein, a plurality of bundles of crimped wire the work engaging end portions of which are longitudinally adjustable through said guide openings, and an axially adjustable ring in which the other 25 ends of said bundles of wire are secured.
6. A rotary roughing tool for shoe parts comprising a hollow shaft, a frusto-conical head having a plurality of outwardly diverging guide openings therein, a corresponding plurality of bundles of wire bristles disposed in parallel relation within the shaft and having their work engaging end portions directed outward through said guide 30
- openings, an axially adjustable ring in which the other ends of the wire bristles are secured, means for moving the ring to adjust the bristles through the guide openings, and a clamping device to secure the bundles of bristles in adjusted position 5 in the guide openings.
7. A rotary roughing tool for shoe parts comprising a tubular shaft, an axially disposed adjusting screw in the shaft, an adjusting ring threaded upon said screw, bristles disposed in 10 the shaft parallel to its axis and having their inner ends secured in said ring, a tool head secured to the end of the shaft and having outwardly diverging channels in which the portions of the bristles near their outer ends are arranged, 15 and a clamping plate provided with blocks arranged to bear upon the bristles in the channels and clamp them in position therein.
8. A rotary roughing brush having a hollow, tubular housing, a tool head, and long bristles 20 mainly disposed in said housing parallel to the rotational axis of the brush, the work engaging end portions of the bristles diverging outward from said axis and being held in divergent relation in said head.
9. A rotary roughing brush having a hollow, tubular housing, a tool head, long bristles mainly disposed in said housing parallel to the rotational axis of the brush, the work engaging end portions of the bristles being held in said 30 head in divergent relation, and means for adjusting the bristles lengthwise in said housing and through said head.

CHARLES G. BROSTROM.
